CIGAR MACHINE BELT FEED CONTROL

Henry H. Wheeler, Brooklyn, N. Y., assignor to
International Cigar Machinery Company, a
corporation of New Jersey

Application January 9, 1934, Serial No. 705,967
Renewed May 7, 1937

5 Claims. (Cl. 131—39)

This invention relates to automatic filler feeds for fresh work cigar machines, of the type in which a layer of filler tobacco is automatically fed into a charge forming device in the proper amount and at suitable intervals to form successive charges of the size and density required for making the cigar bunch.

The present invention relates to filler feeds such as disclosed in Patent No. 1,791,558, granted Feb. 10, 1931, on the application of V. G. Hanson, and particularly to improved means for controlling the feed to the charge forming device. Accordingly, the main object of the invention is to produce improved means for controlling the feed to the charge forming device, so that the successive charges formed therein will be uniform and contain a predetermined volume of tobacco at a predetermined density.

Another object is to provide control means in such a filler feed which are simple in construction yet positive and reliable in action and also quick acting, so that the feed stops immediately on attaining the desired volume and density of the tobacco in the charge forming means. With these and other objects not specifically mentioned in view, the invention consists in certain constructions and combinations hereinafter fully described and then specifically set forth in the claims hereunto appended.

30 In the accompanying drawings which form a part of this specification, and in which like characters of reference indicate the same or like parts:

Fig. 1 is a side elevation of the improved filler feed device; and

35 Fig. 2 is an enlarged top view, partly in section, of the feed control clutch, taken on line 2—2 of Fig. 1.

In carrying the invention into effect there is provided a continuously rotating driving member, a shaft on which said member is loosely mounted, a friction roller-clutch connecting said driving member and shaft, and normally operative to drive said shaft, a feed drum fixed on said shaft, a filler feeding belt driven by said shaft, means for receiving a charge of filler tobacco from said belt, a yielding member disposed in said means to be pushed by the tobacco delivered to said means by said belt, mechanism connecting to said yielding member to incapacitate said clutch when the charge in said means attains a predetermined density, and a device for rehabilitating said clutch. In the best constructions contemplated the clutch includes a driven member fixed on said shaft and provided with notches in

its periphery, a collar on the driving member surrounding the driven member, a ratchet loosely mounted on said shaft, rollers disposed in said notches and carried by said ratchet, and a tension spring connected to the driven member and ratchet and normally holding the latter in position to cause said rollers to jam between the collar and notches; the clutch incapacitating mechanism preferably includes a pawl adapted to engage the ratchet and a counter-weighted trip connected to the yielding member and holding the pawl out of engagement with the ratchet until the pressure of the tobacco on the yielding member is sufficient to overcome the resistance of the trip and disengage it from the pawl, whereby the latter will engage the ratchet and thus stop the rotation of the driven member and shaft; and the clutch rehabilitating device includes a cam-piece on said collar adapted to disengage the pawl from the ratchet. The particular structure selected to illustrate the invention is but one of many possible concrete embodiments of the same, and the invention therefore is not to be restricted to the specific structure shown and described. Furthermore, certain parts of the invention are capable of use independent of the other parts, and such use is contemplated.

Referring to Figs. 1 and 2, the filler feed mechanism is mounted on side frames 9 and 10 which are fastened to the base 11 of the cigar machine, of which the present device is a part. The feed drum 13 is carried by a shaft 12 provided with a hand wheel (not shown), and this shaft is driven from the main drive of the cigar machine by a chain 15 on a sprocket 16 which revolves loosely on the shaft 12 and carries a flange 17 which is attached to or integral with a collar 18. The sprocket 16 rotates continuously on shaft 12 and constitutes the driving member of the filler feed. A ratchet wheel 19 loose on shaft 12 carries a set of studs 20 attached to which are rollers 21, engaging in triangular notches 22 of a driven member 23 keyed to shaft 12.

The member 23 fits within the surrounding collar 18; the rollers 21 are adapted to jam against the interior of collar 18 while it rotates in the direction indicated by the arrow in Fig. 1. For this purpose the notches 22 are so disposed that they provide tapering spaces in which the rollers 21 fit loosely between the member 23 and collar 18 when near the apex of the notches and jam against the collar when carried towards the other end of the notches by the movement of member 23, the ratchet 19 normally being held in position to jam the rollers 21 against the collar 18.

by a spring 24 spanned across the posts 25 and 26 fixed in ratchet 19 and driven member 23, respectively. The upper portion of ratchet 19 is provided with a longitudinal recess 27 thus permitting the spring and posts to be confined within the ratchet. The construction and operation of this type of clutch, which may be termed a friction roller-clutch, is well known so further description thereof is deemed unnecessary.

10 The post 26 projects through a bore 28 in the bottom of recess 27 permitting relative movement of the post 26 with respect to the post 25 while the rotation of the ratchet 19 is stopped. A spring tensioned pawl 29 pivotally mounted on a stud 30 carried by the frame 10, when engaging the ratchet, stops the rotation of member 23 and shaft 12, the sprocket 16 and collar 18 meanwhile revolving idly around shaft 12. A cam piece 31 attached to the collar 18 periodically engages 15 a roller 32 carried by the pawl and swings the same away from the ratchet. When the pawl 29 is disengaged from the ratchet 19, the motion of 20 sprocket 16 is again transmitted to the member 23 when the rollers 21 gradually jam against the 25 interior of collar 18, thus turning drum 13.

The feed belt 33, on which the filler tobacco is spread and which is driven by drum 13, is guided by stationary pulleys 34 and 35, and adjustable pulley 36, and its working portion is 30 supported by a plate 37 extending between the pulleys 34 and 35. One end of plate 37 rests on a tie rod bracket 38 and carries a bearing bracket 39 for supporting the pulley 35. The pulley 34 may be similarly supported from the 35 other end of plate 37, and the pulley 36 may be adjustably supported as shown in the Hanson patent referred to above.

The filler tobacco spread on the upper run of feed belt 33 is carried under leveling star wheels 40, the filler tobacco upon emerging from the leveling wheels continuing its advance under guides 41 to the small feed wheels 42. The feed wheels 42 which move the filler layer after it has left the feed belt 33, pass it on to the platform 43 upon which it rests under the guides 44. Guides 41 and 44 may be adjustably supported as shown in the above mentioned patent whereby they may be raised or lowered to control the thickness of the bunch charge. The supporting 50 and driving means of the star wheels and the feed wheels are disclosed in the patent heretofore mentioned, to which reference may be had for a full disclosure of the same.

Platform 43 and guides 44 together form means 55 for receiving the charge in space 46 between them, the prongs on the upper end of yielding member 45 projecting into said space through slots in platform 43. After the proper volume of tobacco to form a charge has been fed into 60 this space, it is cut off from the mass of tobacco by a knife 47, which is periodically actuated by conventional means, which slides between a shear plate 48 attached to bracket 38 and shear blade 49 fastened to platform bracket 50. After each 65 cut, transfer fingers 50a, the operating means of which forms no part of the present invention, forward the severed bunch charge to a filler transfer, not shown, which carries it to its next operating position in the cigar machine.

70 In forming the charge, the filler tobacco, under the feeding action of the feed belt and the star wheels, advances against the fingers or prongs of the yielding charge arresting plate 45 until the density of the accumulated mass transmits 75 sufficient pressure to balance the weighted arm

51 mounted on one end of the fulcrum shaft 52. The other end of this fulcrum shaft carries an arm 53 which is connected by a rod 54 with a pivoted arm 55 which carries the plate 45. The weights 56 on rod 57 fixed to the weighted arm 51 load the yielding member 45 against the movement by the tobacco in the space 46 until said tobacco has reached a predetermined density. Accordingly, adjustment of these weights will result in regulating the density 10 of the tobacco in the filler charge.

The volume of tobacco in the charge is determined by the extent of the movement or forward travel of the yielding member 45, after the tobacco pushing against said member has reached 15 the desired density. The extent of this movement may be regulated, as will be presently described. The arm 51 rests on adjusting screw 51a while the charge forming space 46 is empty or in the process of being filled, as long as there 20 is insufficient pressure on charge arresting plate 45 to lift the arm 51.

When the accumulated tobacco in the charge receiving space has sufficient density to transmit the motion of the advancing filler to the member 25 45, the trip 58 on the weighted arm 51 swings away from the protruding end 59 of the spring-tensioned pawl 29, thus allowing the latter to engage with the ratchet 19. At the moment the pawl engages the ratchet, the rollers 21 and 30 post 25 in ratchet 19 are stopped while the post 26 in the member 23 continues to move until the tension of spring 24 is sufficient to hold the driven member 23 stationary whereby the rollers 21 are freed from the collar 18 and held in their 35 loose position between the collar 18 and member 23. In this manner the motion of shaft 12 and drum 13 is stopped. It will be seen that this arrangement will result in almost instantaneous discontinuing of the drive whenever the 40 trip 58 releases the pawl 29. The weighted arm 51 is fast to shaft 52 and trip 58 is loose on shaft 52 for adjustment thereon by adjusting screws 58a bearing against the tail of arm 51 and holding the trip securely in its adjusted 45 position when they are tightened, whereby the initial angular position of the trip 58 while holding the pawl 29 away from the ratchet 19 may be adjusted, thus regulating the distance through which trip 58 must be swung to release the pawl. 50 In this manner the volume of tobacco in the charge may be closely controlled, since the initial angular position of the trip 58 may be adjusted within a wide range under the protruding end 59 of the pawl. A further advantage 55 is inherent in this arrangement, since the wearing away of the rear edge of the under face of the end 59 of the pawl will have no appreciable effect on the distance through which the trip swings in releasing the pawl or on the volume of 60 tobacco in the charge. In the form disclosed the length of lever 55 is nearly equal to the length of arm 58, and the distance traveled by yielding member 45 is therefore approximately the same as that traveled by the nose arm 58 in 65 releasing clutch releasing pawl 59. This relationship of elements makes possible a more positive control of the trip release and substantially eliminates over or under feed of filler tobacco. The same cannot be said of prior constructions, in which the parts of the tripping mechanism move through relatively short paths so that any wearing of the same will produce a considerable variation in the volume of tobacco in the charge.

In the rest position of the feed belt 33, the compacted and measured filler charge is cut into bunch lengths by the knife 47 and the member 45 is pulled down by the rod 60 attached to one of the studs 61 which connect the side arms 55 of retaining plate 45 with the end of frame 62 swinging on shaft 63 supported by side frames 9 and 10, the rod 60 being operated by a cam of the cigar machine, not shown.

10 After the cut charge has been removed by the transfer fingers 50a, the member 45 is again raised into tobacco arresting position. At the same time, the continued rotation of collar 18 carries the cam piece 31 around the shaft 12 until said cam piece engages the roller 32 of pawl 29 and disengages the same from ratchet 19, thereby starting the rotation of member 23 and feed drum 13 to deliver the filler tobacco for the next charge.

20 What is claimed is:

1. In an automatic filler feed for cigar machines, the combination with a continuously rotating driving member, of a shaft on which said driving member is loosely mounted, a friction roller-clutch connecting said driving member and shaft, and normally operative to drive said shaft, a feed drum fixed on said shaft, a filler feeding belt driven by said drum, means for receiving a charge of filler tobacco from said belt, a yielding member disposed in said means to be pushed by the tobacco delivered to said means by said belt, and mechanism connected to said yielding member for incapacitating said clutch when the charge of tobacco in said means attains a predetermined density, said clutch including a driven member fixed on said shaft and provided with triangular notches in its periphery, a collar on said driving member surrounding said driven member, a ratchet loosely mounted on said shaft, 40 rollers disposed in said notches and carried by said ratchet, and a tension spring connected to said driven member and ratchet and normally holding the ratchet in position to cause said rollers to jam between said collar and notches, and 45 said mechanism including a pawl adapted to engage said ratchet, and a counter-weighted trip connected to said yielding member and adapted to hold said pawl out of engagement with said ratchet until the pressure of the tobacco on said yielding member is sufficient to overcome the 50 resistance of said trip and swing the latter away from said pawl, whereby the pawl will engage said ratchet to stop its rotation and thus free said rollers from said collar and stop the rotation of said shaft.

55 2. In an automatic filler feed for cigar machines, the combination with a continuously rotating driving member, of a shaft on which said driving member is loosely mounted, a friction roller-clutch connecting said driving member and shaft, and normally operative to drive said shaft, a feed drum fixed on said shaft, a filler feeding belt driven by said drum, means for receiving a charge of filler tobacco from said belt, a yielding member disposed in said means to be pushed by the tobacco delivered to said means by said belt, and mechanism connected to said yielding member for incapacitating said clutch when the charge of tobacco in said means attains a predetermined density, a device for rehabilitating said clutch, said clutch including a driven member fixed on said shaft and provided with triangular notches in its periphery, a collar on said driving member surrounding said driven member, a ratchet loosely mounted on said shaft,

rollers disposed in said notches and carried by said ratchet, and a tension spring connected to said driven member and ratchet and normally holding the ratchet in position to cause said rollers to jam between said collar and notches, 5 said mechanism including a pawl adapted to engage said ratchet, and a counter-weighted trip connected to said yielding member and adapted to hold said pawl out of engagement with said ratchet until the pressure of the tobacco on said yielding member is sufficient to overcome the 10 resistance of said trip and swing the latter away from said pawl, whereby the pawl will engage said ratchet to stop its rotation and thus free said rollers from said collar and stop the rotation of said shaft and said device including a cam-piece on said collar adapted to disengage said pawl from said ratchet.

3. In an automatic filler feed for cigar machines, the combination with a continuously rotating driving member, of a shaft on which said driving member is loosely mounted, a friction roller-clutch connecting said driving member and shaft, and normally operative to drive said shaft, a feed drum fixed on said shaft, a filler feeding belt driven by said drum, means for receiving a charge of filler tobacco from said belt, a yielding member disposed in said means to be moved by tobacco delivered to said means by said belt, and mechanism for incapacitating said clutch 20 and stopping the movement of said belt when the charge of tobacco in said receiving means attains a predetermined density, said mechanism including a clutch releasing device normally held in a position away from said clutch, a trip 25 arm cooperating with said device to releasably support it in said position, and a connection between said yielding member and trip arm so arranged that when said member is displaced 30 a predetermined distance, said device is released 35 for cooperation with said clutch to stop the rotation of said drum, and thereby prevent the feed of additional tobacco to said charge receiving means.

4. In an automatic filler feed for cigar machines, the combination with a continuously rotating driving member, of a shaft on which said driving member is loosely mounted, a friction roller-clutch connecting said driving member and shaft, and normally operative to drive said shaft, a feed drum fixed on said shaft, a filler feeding belt driven by said drum, means for receiving a charge of filler tobacco from said belt, a yielding member disposed in said means to be moved by tobacco delivered to said means 45 by said belt, and mechanism for incapacitating said clutch and stopping the movement of said belt when the charge of tobacco in said receiving means attains a predetermined density, said mechanism including a clutch releasing device 50 normally held in a position away from said clutch, a trip arm cooperating with said device to releasably support it in said position, a connection between said yielding member and trip arm so arranged that when said member is displaced 55 a predetermined distance, said device is released for cooperation with said clutch to stop the rotation of said drum, and thereby prevent the feed of additional tobacco to said charge receiving means, and a device for rehabilitating 60 said clutch, said device including a cam mounted upon said driving member adapted to lift said device from cooperative engagement with said clutch and reestablish the feed of tobacco to the 65 charge forming means.

5. In an automatic filler feed for cigar machines, the combination with a continuously rotating driving member, of a shaft on which said driving member is loosely mounted, a friction roller clutch connecting said driving member and shaft, and normally operative to drive said shaft, a feed drum fixed on said shaft, a filler feeding belt driven by said drum, means for receiving a charge of filler tobacco from said belt, a yielding member disposed in said means to be moved by tobacco delivered to said means by said belt, and mechanism for incapacitating said clutch and stopping the movement of said belt when the charge of tobacco in said receiving means at-

tains a predetermined density, said mechanism including a clutch releasing device normally held in a position away from said clutch, a trip arm, means on said arm engaging with and supporting said device in a position away from said clutch, and connections between said yielding member and means so arranged that when said member moves a predetermined distance, said means is moved approximately the same distance to release said device for cooperation with said clutch and prevent thereby the feed of additional tobacco to said charge receiving means. 5 10
